UNITED STATES PATENT OFFICE.

HERMAN A. PAQUETTE, OF CHICAGO, ILLINOIS.

BURNER.

1,391,494.

Specification of Letters Patent. Patented Sept. 20, 1921.

Original application filed June 10, 1920, Serial No. 387,821. Divided and this application filed August 5, 1920. Serial No. 401,409.

To all whom it may concern:

Be it known that I, HERMAN A. PAQUETTE, a citizen of the United States, residing at Chicago, in the county of Cook and State 5 of Illinois, have invented a new and useful Improvement in a Burner, of which the following is a specification.

My invention relates to burners and more particularly to gas-burners for stoves, boilers, and other structures wherein it is desired to maintain an intense heat or hot flame 10 for domestic and similar purposes. The present application is a division of the application for Letters Patent of the United 15 States filed by me June 10th, 1920, Serial Number 387,821, for improvement in a "Gas stove and burner."

One of the objects of my invention is the provision of a gas-burner constructed with 20 adjustable means for mixing gas with air so that a uniform and perfect combustion may be obtained. Another object is the provision of a burner of this type that is so constructed that the quantity of fuel consumed is materially less than other burners used for similar purposes. Other objects 25 are the provision of a burner that is dependable and effective in performing the functions for which it is designed; that is simple in construction; made of a minimum of parts; easy to install, and comparatively inexpensive to manufacture so that it may be sold for a moderate price.

Other objects will be apparent after my 30 invention is understood and I prefer to accomplish the divers objects in substantially the manner hereinafter described, reference being now made to the accompanying drawings that form a part of this specification.

In the drawings:

Figure 1 is a vertical axial section of my burner and,

Fig. 2 is a perspective view of the gas and air mixing device employed in connection with the burner.

The drawings are in a sense merely diagrammatical illustrating a typical burner, and I have employed the same reference characters to designate the same parts throughout the views.

Referring more particularly to Fig. 1 it will be seen the burner which I have devised preferably comprises a pipe 17 leading from a suitable source of gas supply, 55 which pipe is threaded upon its end. An

elbow coupling 18 is screwed upon this threaded end of pipe 17 and has its opposite stub disposed vertically to discharge in an upwardly direction and is threaded both interiorly and exteriorly. A tip 19 is tapped 60 into the upturned end of the elbow coupling and is provided with a central bore 20 of suitable diameter that extends into the stub 21 of said tip that is preferably reduced in diameter and extends axially up from the 65 upper surface of the tip 19.

Adjacent its upper end the bore of the stub 21 is reduced in diameter to provide a discharge orifice 22, as seen in the drawings. A tube 23 is screwed down upon the exterior 70 threads of the elbow 18, and is provided with lateral ports 24 for the passage of air therethrough into the interior thereof. This tube 23 extends upwardly into the stove or heater a suitable distance and provides a 75 burner on the principle of the well-known Bunsen-type of burner.

From the foregoing it will be seen that the air and gas are respectively admitted to the burner through ports 24 of the tube and 80 orifice 22 of the tip. In order to effectively mix the gas and air, I have provided tube 23 with a regulator, which is shown in detail in Fig. 2 of the drawings. This regulator comprises a split cylindrical tube 32 85 one end whereof is provided with rectangular extensions 33 that are bent laterally inwardly toward the center of the cylinder and are of such length that their corners approximate so as to provide quadrant spaces 90 34 and a central rectangular space 35. The extensions, when thus formed, provide a cross at the inner end of the cylinder 32 which is innermost in the tube 23, and the split portions of the cylinder 32 permit its 95 adjustment up and down within the tube 23 to regulate the character of flame to be discharged from the end of the burner. It will be found after a little experiment that but a slight longitudinal movement or adjustment of this regulator within the tube 23 will materially alter or modify the character of the resultant flame.

What I claim is:

1. A gas burner comprising a gas discharge nipple, a tube surrounding and spaced from the orifice of said nipple and having air inlet ports in its lower portion, and a flame control device consisting of a split tube frictionally mounted within and 110

longitudinally adjustable of said first-mentioned tube and having lateral elements extending radially thereof to partially interrupt the bore.

5 2. A gas burner comprising a gas discharge nipple, a tube surrounding and spaced from the orifice of said nipple and having air inlet ports in its lower portion, and a flame control device consisting of a

blank of metal formed into a cylinder with 10 tongues extending longitudinally therefrom, said cylinder being mounted within said tube and said tongues being bent laterally to partially interrupt the bore thereof.

Signed at Chicago, county of Cook and 15 State of Illinois, this second day of August, 1920.

HERMAN A. PAQUETTE.
